UNITED STATES PATENT OFFICE.

SAMUEL FLOERSHEIMER, OF NEW YORK, N. Y.

DESIGN FOR A WAIST.

SPECIFICATION forming part of Design No. 31,425, dated August 15, 1899.

Application filed June 21, 1899. Serial No. 721,382. Term of patent 3½ years.

To all whom it may concern:

Be it known that I, SAMUEL FLOERSHEIMER, citizen of the United States, residing in the city, county, and State of New York, have invented and produced a new and original Design for a Waist, of which the following is a specification, reference being had to the drawings accompanying and forming a part thereof.

In said drawings, Figure 1 is a front view of the waist, and Fig. 2 is the side view.

Referring to the drawings in detail, A designates the waist, which is provided with two front pieces B, which extend from the central vertical line of the waist in front over to the rear side of the upper portion of the sleeves, forming the front ornamentation, and continuous therewith a sleeve-cap portion C, extending from the point of the shoulder over the top of the sleeve. By this ornamentation a broad

square-shouldered effect is produced, in which the sleeve-cap ornamentation and the front ornamentation are merged into one, the downwardly-extending sleeve-cap portion giving an epaulet-like ornamentation continuous ²⁵ with the front pieces B.

The leading feature of the design consists of the front pieces B, having as a continuation or extension therewith the cap-pieces C, which extend downwardly from the point of ³⁰ the shoulder over the top of the sleeve toward the elbow.

I claim—

The design for a waist as herein described and shown.

SAMUEL FLOERSHEIMER.
